UNITED STATES PATENT OFFICE.

ORPHA MAE KLINKER, OF LOS ANGELES, CALIFORNIA.

DOLL.

1,333,118.

Specification of Letters Patent.

Patented Mar. 9, 1920.

Application filed October 20, 1919. Serial No. 332,052.

To all whom it may concern:

Be it known that I, ORPHA MAE KLINKER, a citizen of the United States, residing at Los Angeles, in the county of Los Angeles,

5 State of California, have invented new and useful Improvements in Dolls, of which the following is a specification.

In the present invention a doll is provided by the combination of a spoon, a dishmop, a floormop, a dishcloth and a dustcloth. The doll provided by the combination of these elements or articles is not only an attractive and durable toy, but is also capable of being easily taken apart so that 15 the various parts may be used for their designed purposes.

A particular feature of the doll is the extreme simplicity of arrangement and construction. None of the parts or articles 20 used in the doll are altered or injured by their use in the combination.

A further feature of the invention is its cost. The articles out of which the doll is made are inexpensive and at the same time 25 standard, useful, household utensils which when taken out of the combination may be used in the household. The cost of assembling or making the doll is very little, as no inconvenient or complicated means 30 are employed in assembling or holding the parts in place. The sightlessness and utility of the doll are also important features as the doll is both sightly and practically indestructible. The combination makes a 35 novelty, a pleasing gift; and makes, as a doll to be used as such, a very pleasing and attractive toy.

Further objects and features of the invention will be readily understood from 40 the following detailed description of a preferred form of the invention in which reference is had to the accompanying drawings in which—

Figure 1 is a sectional view through the 45 doll showing clearly the arrangement of the various parts; and Fig. 2 is a front view of the doll with the hidden part shown in dotted lines.

In the drawings numeral 10 designates 50 the spoon which is preferably a wooden spoon comprising a handle 11 and a bowl 12. The handle 11 is preferably a straight round handle while the bowl 12 is preferably an ordinary shaped bowl. The 55 spoon 10 is set so that the inner or concave portion 13 of bowl 12 faces inwardly and

the outer or convex portion 14 of the bowl faces outwardly. The outer or convex portion 14 of the bowl 12 forms the face of the doll. The features, such as the eyes, 60 nose, mouth, etc., of the face may be painted directly on the surface 14 or they may be printed, painted, or (stamped) on a piece of paper which may be pasted or attached to the surface 14. The surface 14 being 65 convex is particularly well adapted to form the face of the doll.

A dishmop 15 comprising a handle 16 and a swab 17 is lashed or tied to the spoon 10 by means of cord 18. The swab portion 17 70 of the dishmop comprises a bundle of string which is bound to the end of the handle 16 by means of binding cord 19. Although it is preferred to use the form of dishmop shown in the drawings, the invention is 75 not limited to this particular form of mop as any similarly constructed mop could be used in this connection. The dishmop 15 is lashed or bound to the spoon handle so that the handle 16 is parallel with the 80 handle 11 and the portion of the dishmop where the swab is connected to the handle is opposite the bowl of the spoon as shown in Fig. 1. The strings which form the swab 17 are draped or arranged so that part of 85 them extend over and cover the end of bowl 12 as clearly shown in the drawings, while the rest of them are draped or arranged so as to form the head of the doll. The swab 17 being made of strings has the general appearance of being hair when arranged as just described. In order to prevent disarrangement of the swab 17 a ribbon 20 is wrapped around it and tied so as 90 to form a bow 21 as clearly shown in the 95 drawings. The ribbon 20 as well as holding the swab 17 in place acts as a hair ribbon which adds to the beauty of the doll.

A floor slasher or mop 22 comprising a bunch of small strings or thread tied or 100 bound together at 23 is wrapped around the handles 11 and 16 so as to form the body of the doll. The portion 23 of the mop 22 is preferably placed around the handle so as to be at the top or near the bowl 12 105 and thereby form the shoulders of the doll. It is also preferred that the portion 23 of the mop 22 be placed around the handles 11 and 16 so that it is passed around the back of the doll but does not pass completely 110 around the front, in other words, the portion 23 is arranged so that it does not com-

pletely encircle the handles 11 and 16 (this is clearly shown in the drawings). The loose threads which hang downwardly from the portion 23 are arranged so as to completely surround the handles 11 and 16 and thereby cover them. The threads which comprise the mop 22 are all approximately of the same length and when draped are arranged around the handles 11 and 16 as shown in the drawings form a skirt for the doll. The floormop 22 is held in place in relation to the spoon and dishmop by a cord 24 which is bound around said mop substantially at the waist of the doll. The cord 24 being bound around the mop 22 at the waist of the doll not only holds the mop firmly in place but also adds to the shapeliness of the doll.

A duster or dustcloth 25 is held between the cords 24 and the floormop 22 at the front of the doll so that it will hang downwardly over the front of the mop 22 so as to form an apron. The dust rag 25 which is preferably a loosely woven or soft cloth, such as cheese-cloth is arranged so that it is of double thickness and it may be gathered at the top so that a cloth of considerable size can be used. It may also be of single thickness but a large square piece of cloth may be folded over the cord that extends around the waist and then the cloth may be pushed together to the front to give the effect of gathering, thus making it easier to assemble and also does not impair the dustcloth in the least. Although it is preferred that the dustcloth 25 be arranged to extend across the front of the doll only and that it be arranged so that it does not extend to the bottom of the floormop 22 it will be understood that the dustcloth could be arranged so as to extend completely around the doll so as to form a skirt or covering for the mop 22.

A dishcloth 27 which may be knitted or woven is wrapped around the shoulders and upper portion of the body of the doll so as to form a shawl. The dishcloth 27 is preferably placed around the doll so that its ends overlap at the front of the doll as shown in Fig. 2. The dish cloth 27 being wrapped around the upper portion of the body of the doll completely covers the portion 23 of the floormop and the cord 24 which holds said mop in place. It is preferred that the dishcloth be arranged around the doll so that it has a portion 28 which will extend slightly under the portion of the swab 17 which forms the back of the head of the doll. When the dishcloth is arranged in this manner both the spoon 10 and the handle of the dishmop cannot be seen from the back of the doll. The dishcloth 27 may be lightly sewed or basted to the floormop 22 at several points, but it is preferred that it be lightly sewed or basted together where it overlaps at the front of the doll.

It has been found in practice that the various articles out of which the doll is formed, although all light in color vary somewhat in shade, for instance, the dishcloth although white is not exactly the same shade as the dustcloth and the floormop is still another shade. This slight contrast in color of the various articles or parts of the doll greatly add to the appearance of the doll. Although it is preferred that the various articles be left in their natural state, that is, not colored it will be understood that the various parts could be colored with dyes, that would readily wash out, and thereby greatly add to the attractiveness of the doll.

Having described a preferred form in which the invention may be embodied, I do not wish to limit myself to the details as hereinabove set forth, but wish to reserve to myself any changes or variations that may fall within the scope of the following claims.

Having described a preferred form of my invention, I claim:

1. A doll comprising a spoon having a handle and a bowl, said bowl forming the face of the doll, a dish mop comprising a handle and a swab, said swab set adjacent to said bowl to form the hair of said doll, a floormop below said bowl and swab forming the body of the doll, a dustcloth suspended from the floormop forming an apron, and a dishcloth around the upper portion of the body forming a shawl.

2. A doll comprising a spoon having a handle and a bowl, said bowl forming the face of said doll, and said handle extending downwardly from said bowl, a dishmop having a handle and a swab, said swab adjacent to said bowl forming the hair of the doll, and said handle extending downwardly from said swab, a floormop adjacent to the lower portion of said bowl and extending downwardly around said handles forming the body of the doll, a dustcloth attached to said floormop at the middle of said floormop and extending downwardly forming an apron for the doll, and a dishcloth around the upper portion of the floormop and joining at the front of the floormop forming a shawl for the doll.

3. A doll comprising a spoon having a handle and a bowl said bowl having a convex portion forming the face of the doll, a dishmop comprising a swab mounted on a handle, means for attaching the handle of said dishmop to the handle of said spoon so that the portion of the dishmop where the handle joins the swab is adjacent to the bowl of said spoon allowing a portion of said swab to overhang the top of the bowl of said spoon, a floormop in connection with said handles so as to completely cover said handles and form the body and skirt of the doll, means for attaching said floormop to said handles at the middle of said floormop

5 forming the waist of said doll, a dishcloth wrapped around the upper portion of said floormop slightly overlapping at the front of the floormop to form a shawl, and a dustcloth attached to the floormop at the front of the waist of the doll and allowed to hang downwardly over the skirt to form an apron.

10 4. A doll comprising a spoon having a handle and a bowl, said bowl having a convex portion forming the face of the doll, and said handle extending downwardly from said bowl, a dishmop having a handle and a swab, said swab adjacent to and behind said bowl forming in connection with 15 said bowl the head of the doll, and said handle extending downwardly from the head of the doll parallel and adjacent to the handle of said spoon, means for holding the handle of the spoon in connection 20 with the handle of the dishmop, a floormop adjacent to the lower portion of the head of the doll and extending downwardly around said handles and below the ends of said handles to form the body and skirt of 25 the doll, a dustcloth connected to the front of said floormop forming an apron to cover the front of the skirt of said doll, and a dishcloth around the body of said doll having slightly overlapping ends at the front 30 of the body forming a shawl for the doll.

35 5. A doll comprising a spoon having a handle and a bowl, said bowl forming the face of the doll, a dishmop comprising a handle and a swab, said swab set adjacent to said bowl to form the hair of said doll, and a floormop below said bowl and swab forming the body of the doll.

6. A doll comprising a spoon having a handle and a bowl, said bowl forming the face of the doll, a dishmop comprising a handle and a swab, said swab set adjacent to said bowl to form the hair of said doll, a floormop below said bowl and swab forming the body of the doll, and a dustcloth suspended from the middle of said floormop. 45

7. A doll comprising a spoon having a handle and a bowl, said bowl having a convex portion forming the face of the doll, and said handle extending downwardly from said bowl, a dishmop having a handle and a swab, said swab set adjacent to and back of said bowl forming in connection with said bowl the head of the doll, and said handle extending downwardly from said swab parallel and adjacent to the handle of said spoon, means for connecting said handles, a floormop adjacent to the lower portion of the head of said doll and extending downwardly around said handles forming the body and skirt of the doll, means for attaching said floormop to said handles, a dustcloth attached to said floormop at the middle of said floormop and extending downwardly forming an apron to cover the front of the doll and dishcloth and around the body of the doll having slightly overlapping ends at the front of the body forming a shawl for the doll. 55

In witness that I claim the foregoing I have hereunto subscribed my name this 30th day of September 1919. 60
